UNITED STATES PATENT OFFICE.

SIDNEY A. REEVE, OF TOMPKINSVILLE, NEW YORK.

RAILWAY-CAR.

1,300,776.

Specification of Letters Patent. Patented Apr. 15, 1919.

Application filed March 2, 1916. Serial No. 81,670.

To all whom it may concern:

Be it known that I, SIDNEY A. REEVE, a citizen of the United States, residing at Tompkinsville, in the county of Richmond 5 and State of New York, have invented a new and useful Railway-Car, of which the following is a specification.

My invention relates primarily to cars used interchangeably as sleeping-cars and 10 day-cars, and has for its object an improvement in carrying-capacity, combined with increased privacy and comfort for the passengers, both by night and by day; but some of its advantages apply to day-cars. 15 Broadly speaking, my invention consists in the better utilization of the space available in the car. This is accomplished by placing the aisle at one side of the car and locating the seats or berths transversely to the 20 car along its other side, making the transverse length of seat sufficient for a recumbent person, yet reserving a small standing-space at the end of each berth, between it and the aisle; and by making the seats or 25 berths, in their daytime aspect, reversible as to face, so that all passengers may sit facing in the direction of the car's motion and no passenger need face any other, except at will. At night each seat or berth is partitioned from its neighbors, making of each 30 a small compartment or stateroom; yet in the daytime the car is left open from end to end and free from the objectionable fixed partitions of the so-called "compartment-car" now in use.

The standing-room at the foot of each seat or lower berth, inside a curtain separating the compartment from the aisle, permits the provision of each compartment with its own 40 wash-basin. The space thus saved at the end of the car by the omission of the usual public wash-room, coupled with more economical dimensions of each berth, permits the location of about thirty per cent. more 45 berths in a car of given length than is possible in the arrangement of sleeping-car now most common. For in this latter arrangement the width of each berth is fixed, by the use of a central aisle with longitudinal 50 berths, at a dimension greater than is needed for the comfort of a single re-

cumbent passenger, yet not wide enough for comfort for two. Thus space is wasted. But in my arrangement specified herein below the width of berth may be adjusted by 55 the car-designer to that sufficient for the comfort of a single passenger, and no more. The space thus saved permits the allotment to each lower berth of a small private dressing-room, yet also permits a larger number 60 of lower berths than in the arrangement now customary.

A preferred embodiment of my invention is shown in the drawings, to show how space may be saved in the manner just specified. 65 In the drawings, Figure 1 is a vertical cross-section of the car, showing daytime arrangement in full lines and night-time in broken lines. That is to say, the broken lines surrounding the symbol 36 indicate the lowered or night position of the upper berth 34. The remainder of the broken lines indicate the joints between several panels which together constitute a removable partition between each two seats, which partition extends from the top of the seat-back 14 to or near to the roof of the car and from the aisle end of the seat out to the stanchion 26 or the curtain 48. These panels are supported by the various fixed parts of the car 80 with which they come into contact (and by each other) by the usual latches, bolts or other fastenings, whereby they are easily removable and separable for storage during 85 the daytime. This storage is accomplished 85 by making each panel smaller than a single berth, whereby the panel may fit between the upper berth and the car-roof when storage is in the (closed) upper berth, or may lie flat beneath the cushions of the lower 90 berth. Thus the vertical joint shown by the vertical broken line between symbols 38^a and 38^c (Fig. 1) may occur anywhere near to or at alinement with the end of the car-seat 14, according to the dimensions and arrangement of parts selected. This outer panel is 95 separately removable, without disturbance of the remainder of the partition-panels. The curtain 48 is also similarly removable by day, from its night-position shown adjacent to space 112^c (Fig. 3), as is shown near spaces 112^a and 112^b of the same figure. 100

Fig. 2 is a longitudinal vertical section of a portion of the car's length, broken away at various places to show details, showing two seats or compartments in daytime aspect and one in night-time arrangement.

Fig. 3 is a plan section of Fig. 2, reduced in width by fracture through the berth-space.

Fig. 4 is a plan of a modification in which 10 the stanchions 26 are located on the side of space 112 toward the berths, instead of toward the night-aisle 110.

Fig. 5 is a longitudinal diagrammatic section through the berth-space, looking toward the right-hand as in Figs. 1 and 4, 15 showing one end of said berth-space.

Fig. 6 is a vertical cross section of Fig. 4. In the drawings, 10 is the car-body, equipped with windows 11 in the manner 20 usual in so-called "day-coaches," except that the windows are preferably of slightly greater width, or more widely spaced. The general grade of construction of the car-body and trucks is preferably that now 25 standard for parlor-cars and pullmans, but its windows following more the dimensions and number customary in "day-coaches", occupying virtually the entire length of the car.

30 The car's interior space is divided into three general parts, namely, (1) the night aisle 110 along one wall of the car; (2) the seat or berth space 111 along the other wall, occupying about six feet of the width of the 35 car, or slightly over; and (3) the small standing-room space 112 left between the other two. In the daytime the night-aisle 110 and the space 112 combine, by the removal of the curtain 48, to form the regular or daytime aisle. The seats 12 extend 40 transversely across the space 111 and are made reversible in direction of face by the swinging of the seat-backs 14 from one edge of the seat 12 to the other, to 45 suit the direction of motion of the car.

Each end of each seat 12 is supported upon a pin 181 having a fixed support 13, each pin fitting at will into some one or other of the notches 17^a, 17^b or 17^c with which the 50 end of the seat 12 is provided. Each seat is also supported at each end by a pin 18 fixed in a metallic strip or bar 15 attached to each end of each seat-back 14, which bar is supported below by its sharpened end 55 fitting into some one of the notches 16^a, 16^b or 16^c formed in the floor of the car, while the pin 18 bears in a slot 19 formed on the end of seat 12.

In the side-wall of the car next to the 60 seats, between each two adjacent windows, is fixed a plate 241 having a vertical slot 24. Into this slot fits the end of a bolt 23 attached slidably to the seat-back 14. Opposite each such plate 241 is set a vertical post

or stanchion 26, preferably made of tubular 65 metal, extending from floor to roof of car and firmly fixed in place by plates 261 and 262 at floor and top. The aisle-end of each seat-back 14 carries a sliding bolt 25, having a forked end 25^a adapted to engage with 70 its respective post or stanchion 26, with a one-way hinge 50 for folding up the part 25^a. Bolts 23 and 25 are attached by links 22 to a latch 20 swinging on a center 21 fixed to the seat-back 14, whereby the bolts 75 may be engaged with or withdrawn from their respective fixed supports simultaneously.

Figs. 2 and 3 show three seats or compartments, opposite three adjacent windows 80 11^a, 11^b and 11^c, each consisting of berth-space 111^a, 111^b and 111^c respectively and standing-room 112^a, 112^b and 112^c. The seat of berth-space 111^a is shown adjusted to its preferred daytime position, with bar 15 supported at its greatest slant, in notch 16^a, and seat 12 also at a slant, with pin 181 in notch 17^a. The seat of berth-space 111^c is shown adjusted for night-use, with bar 15 supported vertically in notch 16^c and seat 90 12 horizontal, with pin 181 in notch 17^c. The seat of berth-space 111^b is shown in a position intermediate between the two just described, which may be assumed at the taste of the passenger or for convenience 95 when a seat is used for upright purposes adjacent to one adjusted for recumbency. Hinged to the edge of each seat 12 is a supplementary cushioned frame 31, having folding legs 32, which in the daytime is 100 swung back underneath seat 12, as in compartments 111^a and 111^b, and at night is swung into the position shown in compartment 111^c. At night a mattress 33 may be spread over the cushions of 12 and 31. 105

Above each lower berth or seat 12 is an upper berth 34, also arranged transversely to the car, which at night may be swung down on hinges 35 into position 36. It is to be held in each of these positions by suitable latches not shown in the drawings. It may have at its open end a folding portion 37 used either to extend its length or to retain better its bedding in place, or for both purposes. In daytime the bedding for both 115 upper and lower berths may be stored in the space 60 between the upper berth 34 and the roof of the car. In this same space may also be stored the solid partition-panels 38^a, 38^b and 38^c—such a set of three panels being 120 provided for each compartment except one—which, together with the small panel 38^d, form the night-time wall between adjacent compartments. These panels are supported firmly in place by suitable means of 125 attachment to the car-body 10, to each other, to the seat-backs 14, to the stanchions 26, to the upper berths 34 and to the fixed par-

tion 61 demarking the roof-space above each berth from its neighbors, which partition in daytime is hidden by the upper berths 34. These means of attachment are 5 not shown in the drawings. The partition-panel 38^c bears upon its one face a set of ladder-rungs or steps 39 and upon its opposite face a mirror 47.

Along the top of the car, above the stanchions 26, is a water-tank 27, preferably divided into compartments by partitions 29 reaching nearly to the top of the tank, one opposite each seat or berth. The tank is provided with a gate 28 for filling the entire tank with water. Each stanchion 26 may form a water-supply pipe from tank 27 to each compartment's standing-room. Each stanchion may support a wash-basin 43 for each compartment, having drain-plugs leading to a catch-basin 46 whence the waste-water may flow to the outside of the car. Each basin may swing from its position 43 (Fig. 3), corresponding to the direction of car-motion and seat-facing shown, 20 to an alternate position 471 for the opposite direction of car-motion and seat-facing; or the wash-basin may be made easily removable. At night curtains 48 separate each compartment's standing-room from the aisle. The 30 stanchions or posts 26 may be located immediately at the ends of the seat-backs 14 as in Figs. 4 and 6, merely the curtain 48 demarking the standing-room 112 from the aisle 110.

35 A water-closet 150 (Fig. 4) may be provided at each end of the berth-space, with a door 151 opening from space 112. The partition 160 (Fig. 5) forming the end of the berth-space of the car carries a cushion-frame 161 hinged at 162 to the end-partition 160. This frame is shown in full lines for its day-position and in dotted lines for its night-position, and is to be fitted with suitable supports (not shown) for holding it 40 in either position.

The method of use of the car is plain from the above. Manipulation of the latch 20 frees the seat-back 14 for shifting it and the seat 12 into any of the three positions 50 shown in Fig. 2, or for complete reversal of face.

The advantages of my improved arrangement, in addition to that of increased carrying-capacity already described, are those 55 of privacy and convenience, both by night and by day. Such will appeal most to women, although even for men the convenience and time-saving of dressing in one's own compartment, with a separate water-supply for each section, will be of value 60 both to the passengers and the railway-company. The toilet-accommodations in each compartment and the chance to stand inside the curtains while dressing will eliminate

much travel about the car in a half-dressed 65 condition, for both sexes. A woman traveling with children can sit on the end of her berth, with wash-basin at elbow, and can wash and clothe the children before dressing herself. Children can be put to bed in 70 the upper berth without danger of their rolling over the edge; or, if the mother prefers to sleep above, she has a stairway ready for descent at any time, without need of calling the porter to bring one. For family- 75 parties occupying more than two berths two or more compartments can be made into one by omitting the partitions 38, or at least the panels 38^c and 38^d leaving room for 80 passage from one compartment to the other inside the curtain 48. When the partition-panels 38^c and 38^d are absent there is little need for the part 25^a, in the form of my invention shown in Fig. 1, and this may be folded back out of the way by means of 85 the hinge 50. Or, if the stanchions be located well inside the curtains, at the seat-ends, as shown in Figs. 4 and 6, a narrow passageway along the space 112 between the stanchions 26 and curtain 48, will be formed, 90 as in Figs. 4 and 6, open from one end of the car to the other except where the removable partition 38^c, 38^d may interfere. By giving this narrow passageway direct opening into the toilet-room at either end of the 95 car, the omission of panels 38^c, 38^d from partitions near that end of the car will provide a series of compartments (which series forms a stateroom capable of extension to include 100 any number of berths or sections) private and peculiar to the sex belonging to the end of the car in question, each compartment and each sex having a passageway to its respective toilet-room concealed from the public aisle by the curtains 48; and since the 105 boundary between the passageway 112 and the public aisle 110 is demarcated merely by curtains which are in use only at night, and by nothing at all in the daytime, the aisle 110 can in that case be made relatively narrower and the passageway 112 relatively wider than shown, without public inconvenience. But even in the arrangement shown in Figs. 1, 2 and 3 women traveling alone 115 will not have to pass male passengers while dressed in kimono, in order to wash before dressing.

Finally, the greater attractiveness and carrying-capacity of my car in daytime, as 120 compared with previous arrangements of sleeping-cars, or even as compared with parlor-cars, will facilitate the problem of handling traffic by largely reducing the demand for both parlor-cars and sleeping-cars to be run simultaneously over the same division. For second-class through traffic it possesses marked advantages. For in daytime 125 my arrangement permits the comfort of

recumbency at full length while the passenger is virtually concealed from the rest of the car, without making up the compartment as for night-use. This advantage will 5 inhere in my arrangement even in those cars which may never be fully equipped for night-use.

I claim:

1. In a railway-car, the combination of a 10 night-aisle along one side thereof, transverse berths as long as the human form convertible into reversible seats along the other side thereof, and a space intermediate between said aisle and said berths substantially as 15 described.
2. In a railway-car, the combination of an aisle along one side thereof capable of longitudinal subdivision at night by a curtain removable by day and transverse berths convertible into angularly adjustable reversible seats extending substantially from the other side thereof to the aisle substantially as described. 20
3. In a railway-car, the combination of an aisle along one side thereof capable of longitudinal subdivision at night by a curtain removable by day, transverse berths convertible into angularly adjustable reversible seats extending substantially from the other side 25 thereof to said aisle, and removable partitions separating adjacent berths substantially as described. 30
4. In a railway-car, the combination of an aisle along one side thereof, transverse berths convertible into seats extending from the other side thereof, a space between each berth and said aisle, and removable partitions segregating each berth and space together as a compartment substantially as 35 described. 40
5. In a railway-car, the combination of an aisle along one side thereof, removable curtains along the inner side of said aisle, berths extending transversely from the other side 45 of the car nearly to said aisle, a second aisle between said berths and said curtains, and removable partitions adapted to block said second aisle substantially as described. 50
6. In a railway-car, the combination of an aisle along one side thereof capable of longitudinal subdivision at night by a curtain removable by day and transverse reversible seats extending substantially from the other side thereof to said aisle, said seats being adjustable as to angular position of seat and back substantially as described. 55
7. In a railway-car, the combination of an aisle along one side thereof capable of longitudinal subdivision at night by a curtain removable by day, transverse berths convertible into reversible seats extending substantially from the other side thereof to said aisle, and removable solid partitions between adjacent seat-spaces subdivided into 60

panels each smaller than a single berth substantially as described. 65

8. In a railway-car, the combination of an aisle along one side thereof capable of longitudinal subdivision at night by a curtain removable by day, transverse berths convertible into reversible seats extending substantially from the other side thereof to said aisle, and a column supporting each seat-back at its aisle-end substantially as described. 70

9. In a railway-car, the combination of an aisle along one side thereof, transverse lower berths convertible into reversible seats extending substantially from the other side of the car to said aisle, and a transverse upper berth hinged to said other side of the car above each lower berth substantially as described. 75 80

10. In a railway-car, the combination of an aisle along one side thereof, posts near the inner edge of said aisle and transverse reversible seats extending substantially from said aisle to the other side of the car, the backs of said seats being detachably supported by said posts substantially as described. 85 90

11. In a railway-car, the combination of an aisle along one side-wall thereof, vertical posts near the inner edge of said aisle, a vertical slot in the other side-wall of the car opposite each post, and transverse seats as long as the human body convertible into berths between said aisle and said other wall, the back of each seat supported slidably by said post and said slot substantially as described. 95 100

12. In a railway car, the combination of a series of transverse reversible seats each as long as the human body and each convertible into a berth by means of a cushion-frame hinged to the edge of a seat, and a cushion-frame hinged to the end-wall of the car adjacent to a seat-edge lacking the first mentioned hinged frame and adapted to complete the end-berth when said reversible seat is adjusted to face said end-wall substantially as described. 105 110

13. In a railway-car, the combination of an aisle along one side thereof, a second aisle contiguous to the first and demarcated therefrom at night by removable curtains, berths extending transversely from the other side of the car to said second aisle, a water-closet at each end of the car accessible from said second aisle and a removable partition adapted to block said second aisle between two adjacent berths substantially as described. 115 120

14. In a railway-car, the combination of an aisle along one side thereof, a second aisle contiguous to said aisle and demarcated therefrom at night by removable curtains, transverse seats convertible into berths between said second aisle and the other side of 125

the car, removable partitions between adjacent berths extending from said other side to said second aisle, and other similar partitions extending to the first mentioned aisle substantially as described.

15. In a railway-car, an aisle along one side thereof capable of longitudinal subdivision at night by a curtain removable by

day, reversible seats extending transversely from the other side thereof substantially to 10 said aisle, a hollow stanchion between each seat and said aisle supporting the back of said seat, a water-tank in the top of the car and a connection from said tank to said stanchion.

SIDNEY A. REEVE.
